[57] CLAIM

The ornamental design for a carrier for cans or the like,
as shown and described.

DESCRIPTION

FIG. 1 is a perspective view of a carrier for cans or the like showing my new design with one of the carrying straps shown detached from one of the carrier sides;
FIG. 2 is a top plan view with both carrying straps attached to the carrier sides;
FIG. 3 is a bottom plan view thereof;
FIG. 4 is a side elevational view thereof;
FIG. 5 is a view showing the side opposite that seen in FIG. 4;
FIG. 6 is an end elevational view thereof; and,
FIG. 7 is a view showing the end opposite that seen in FIG. 6.
